(57) CLAIM

The ornamental design for a display screen with set of icons, as shown and described.

DESCRIPTION

FIG. 1 is a front view of a display screen with set of icons showing the new design; and, FIG. 2 is a front view of a display screen showing an alternate embodiment thereof.

The broken line showing of the display screen is for environmental purposes only and forms no part of the claimed design.

1 Claim, 2 Drawing Sheets

FIG. 1

FIG. 2
